C. H. SWENSON

EXCAVATING SYSTEM

Filed July 7, 1923

E. Q. Ruppert
P.C. Cannon,

WITNESS:

C. H. Swenson
INVENTOR

BY Victor J. Evans

ATTORNEY

UNITED STATES PATENT OFFICE.

CHARLES H. SWENSON, OF SLIDELL, LOUISIANA.

EXCAVATING SYSTEM.

Application filed July 7, 1923. Serial No. 650,140.

To all whom it may concern:

Be it known that I, CHARLES H. SWENSON, a citizen of the United States, residing at Slidell, in the parish of St. Tammany and

5 State of Louisiana, have invented new and useful Improvements in Excavating Systems, of which the following is a specification.

This invention relates to the process of 10 excavating gravel and sand and has for an object the provision of improved means for this purpose which will increase the output and in addition prevent the material from clogging the casing.

15 Another object of the invention is the provision of a process of this character which is simple, reliable and economical in operation and which may be easily installed.

With the above and other objects in view, 20 the invention further includes the following novel features and details of construction, to be hereinafter more fully described, illustrated in the accompanying drawing and pointed out in the appended claim.

25 In the drawing the figure shown is a diagram illustrating the process.

Referring in detail to the drawing, the 30 reference character 10 indicates a casing which extends into the ground, the top surface of which is indicated at 11. The bottom end of the casing 10 extends into a strata of gravel and water, indicated at 12, while the natural water level within the casing 10 is indicated at 13.

35 The casing extends through the platform 14 and its upper end is in communication with an overflow conduit 15.

Extending downwardly within the casing 40 and having its outer end connected to a pressure pump is a water line 16, whose

lower outlet end extends below the bottom of the casing 10 and into the strata 12 of gravel and water.

As will be readily understood the water will be forced outward through the top of 45 the casing 10 and through the conduit 15 by hydraulic pressure through the pipe 16, the said water carrying with it the gravel and sand, where the latter is present.

One of the novel features of the invention 50 resides in the introduction into the casing, of air under pressure and for this purpose there is provided an air supply pipe 17 through which air under pressure is forced. The discharge end of the pipe 17 is located 55 below the water line 13 and above the discharge end of the pipe 16 and the compressed air forces the water and gravel upward and prevents the casing from becoming clogged with the gravel and sand 60 due to this pressure.

Having described the invention what is 65 claimed is:—

An excavating apparatus comprising a casing open at the bottom and adapted to extend downwardly within the material to be removed, a discharge conduit at the upper end of the casing, a water pipe extending downwardly through the casing with its lower end disposed below the bottom of 70 the casing and its upper end adapted to be connected to the source of water under pressure, a compressed air supply pipe extending downwardly into the casing and an upwardly disposed nozzle at the lower 75 end of the air pipe.

In testimony whereof I affix my signature.

CHARLES H. SWENSON.
